UNITED STATES PATENT OFFICE.

WALTER W. CHAMBERLAIN, OF WATERTOWN, NEW YORK.

CARTON FILLER.

Application filed May 18, 1923. Serial No. 639,855.

To all whom it may concern:

Be it known that I, WALTER W. CHAMBERLAIN, a citizen of the United States, residing at Watertown, in the county of Jefferson and State of New York, have invented certain new and useful Improvements in Carton Fillers, of which the following is a specification.

This invention relates to carton fillers, designed particularly for use by confectioners, and the like, for filling cylindrical cartons with ice-cream, and other products, and has for its object to provide novel and sanitary means for filling the cartons at a single operation. A further object is to provide a hollow cylindrical body for inclosing and holding the cartons during the filling operation, the said body being equipped with a handle by which the device is manipulated, and the said handle and body being separable for facilitating the applying and removing of the cartons. And a further object is to provide means for preventing the over-filling and fouling of the cartons.

I attain these objects by the means set forth in the detailed description which follows, and as illustrated by the accompanying drawings, in which—

Figure 1 is an elevational view of the complete device, showing the handle locked to the body ready for filling a carton. Fig. 2 is a central vertical section, in which parts of the carton are broken away to show the extent of the filling. Fig. 3 is a top-plan view of the device. Fig. 4 is a horizontal section, taken on line 4—4 of Fig. 2. Fig. 5 is an elevational view, showing the handle and body separated. Fig. 6 is a view, showing the body partially inverted and the carton gravitating therefrom. And Fig. 7 is a detached view of the filled carton.

In the drawings, 2 represents a hollow cylindrical body preferably open at both ends, the lower end of which is provided with a circular row of teeth 2', by means of which the body, when rotated like an auger, cuts its way into the more or less solid ice-cream, which is usually kept in relatively large freezers or cans (not shown). The top end of the body 2 is closed during the filling operations, by a cap 3, the latter having a depending flange 3', which receives the body, and may be temporarily locked thereto, by means of pins 2", which project from the opposite sides of the body, and corresponding angular slots 3", which are formed in the

free margin of the said flange (see Figs. 1 and 5). The top of the cap 3 is formed with a concentric hub or sleeve 3", which receives the lower end of the stem 4', of a T-handle 4, by means of which the device is manipulated during the filling of the cartons. The stem 4' may be rigidly secured to the hub by a pin 3".

Preparatory to filling the ordinary cylindrical carton, as 5, the cap 3 and handle 4 are removed from the body 2, as shown in Fig. 5. The cover 5' of the carton is next removed, and the open or mouth-end of the carton is inserted downwardly into the body 2 (see Fig. 2), until the said end comes to a stop against an inwardly facing annular ledge or rib 2", which is formed near the bottom end of the body. The handle and cap are then replaced and locked to the body, as shown in Figs. 1 and 2. In order to prevent the end-wise movement of the carton 5, during the filling operation, a shoulder 3" of the cap is arranged to normally bear against the bottom end of the carton, as shown in Fig. 2. The slots 3" and the pins 2" are arranged to prevent the accidental separation of the cap 3 and the body 2, during the filling operation. The rib 2", in addition to stopping the downward movement of the carton, also serves to seal the joint between the carton and the inner surface of the body 2, and prevents any of the ice-cream or other product, from reaching and fouling the said parts.

The operation of my carton filler, is as follows: Assuming that the device is loaded with an empty carton 5, and the cover 3 is locked in place, as shown in Figs. 1 and 2, the operator grasps the handle 4, and holding the device, as shown in Figs. 1 and 2, inserts the body 2 into the ice-cream container (not shown), until the normally open lower end 2' of the body contacts with the ice-cream. The operator should then exert downward pressure on the filling device, and at the same time twist or rotate the body 2, like an auger, for boring downwardly into the frozen cream, until the flange 3' of the cap sinks substantially its full depth into the ice-cream, which indicates that the carton is filled. Ordinarily, the carton 5 will fill properly at a single operation, provided the requisite pressure is exerted, but, in order to obviate the danger of the imperfect filling of the carton, due to the pres-

ence of air that may be confined in its top or closed end, I provide simple means for venting the carton, which consists of a tapering tube 6, that depends from a bridge 5 6' carried by the cap 3. The free end of this tube is preferably sharp enough to readily puncture the bottom 5^a of the carton (as shown in Fig. 2), by the force exerted in applying the handle to the body 2. 10 By this arrangement, any air that may become entrapped in the carton will be readily forced upwardly through the vent 6, and finally escape through a small opening 4^a of the stem 4'. After the carton 5 is filled, as 15 explained, the device is withdrawn from the main container, and the cap 3 is removed from the body 2, by the turning of the handle 4 in the opposite or leftward direction, for freeing the pins 2^a from the slots 3^a. 20 The body 2 should then be inverted, as shown in Fig. 6, for allowing the release of the filled carton, which is usually effected by gravity. A particular aim of the present invention, is to substantially fill the cartons, and to prevent any of the ice-cream α from showing beyond the level or plane of the mouth 5^b of the carton, when the latter emerges from the body 2. To this end, I provide a wire or "cut-off" 7, which is preferably disposed diametrically across the interior of the body, substantially in the plane of the mouth 5^b of the carton, as shown in Figs. 1, 2, 3, and 4. The wire 7 is preferably of small gauge, so as not to interfere 35 with the boring and filling operation, and during the final rotary movement of the body 2, the wire 7 gauges the filling of the carton, by cutting the ice-cream level or flush with the mouth of the carton, as best 40 shown in Figs. 2 and 7. The provision of the wire 7 not only obviates waste of the ice-

cream by over-filling the carton, but also prevents the cream from smearing and fouling the interior of the cap 5' of the carton. 45

Obviously my device may be employed for filling cylindrical cartons with butter, lard, and other products of like consistency, as well as ice-cream; the construction, arrangement and operation of the device being such that, any person of ordinary skill may apply, fill and remove the cartons in a ready and sanitary manner, and at a single operation. 50

Having thus described my invention, what I claim, is— 55

1. A carton filler comprising a cylindrical body open at both ends and formed at one end with a cutting edge and an inwardly set, inwardly pressed bead, the latter forming a stop shoulder for a carton inserted from the opposite end of the body, a cutting wire stretched across the first end of the body and having its ends secured to the bead, a removable cap closing the said opposite end of the body and formed with a central sleeve, a piercing prong supported at the base of the sleeve, and a hollow handle secured in the sleeve and provided with an air vent. 60

2. A carton filler comprising a body open at both ends for receiving a carton, a removable cap for closing one end of the body having a marginal flange encircling the body and detachably connected therewith, and a piercing prong arranged within the cap and above the lower edge of the flange whereby the prong is protected and concealed by said flange when said cap is removed and resting on its flange. 65

In testimony whereof I affix my signature. 70

WALTER W. CHAMBERLAIN.
